STOP-CASTING.

1,290,308.

Specification of Letters Patent.

Patented Jan. 7, 1919.

Application filed September 20, 1916. Serial No. 121,130.

To all whom it may concern:

Be it known that I, JOHN F. O'CONNOR, a citizen of the United States, residing at Chicago, in the county of Cook and State of Illinois, have invented a certain new and useful Improvement in Stop-Castings, of which the following is a full, clear, concise, and exact description, reference being had to the accompanying drawings, forming a part of this specification.

This invention relates to improvements in stop castings.

Objects of the invention are to provide a stop casting for railway draft riggings wherein the metal of the casting is of substantially uniform thickness throughout and also free from T or other sections that would produce unequal strains in the casting or annealing operations.

Other objects of the invention are to provide a stop casting of the type above outlined which may be cast without the use of cores and wherein great strength is provided against longitudinal and transverse strains, the latter result being obtained by a novel combination of vertical and horizontal convolutions. The invention is in the nature of an improvement on the structure shown in my prior Patents 829,728 of August 28th, 1906 and 862,932 of August 23rd, 1907.

In the drawing forming a part of this specification, Figure 1 is a side elevation of an improved stop casting embodying my invention. Fig. 2 is a horizontal, longitudinal section taken on the line 2--2 of Fig. 1. And Figs. 3, 4, 5 and 6 are vertical sectional views taken on the lines 3--3, 4--4, 5--5 and 6--6, respectively, of Fig. 1.

In said drawing, the stop casting is shown as designed for a tandem gear and is provided with a front main stop 10, center post 11 forming front intermediate stop 12 and rear intermediate stop 13, and rear main stop 14. Limiting stops 15, 16, 17 and 18 are provided in conjunction with the main stops 10, 12, 13 and 14, respectively. The stops are formed by series of vertical convolutions or bends open to the outer or rear side of the casting, as will be seen from the outline of the web of the metal in Fig. 2, the continuous dotted line 19 indicating the thickness of the metal which follows the contour of the stops. As will be understood, those vertical convolutions which form the stops proper are open to the back of the casting

whereas the convolutions intermediate the stops are open toward the inner face or front of the casting, the convolutions being formed by bends in the metal extending alternately inwardly and outwardly.

In order to provide the casting with great strength, the same is made with a series of horizontal bends or convolutions designated A, B, C, D and E. The upper and lower and central horizontal convolutions A, C and E are open toward the back of the casting, whereas the two intermediate horizontal convolutions B and D are open to the front of the casting. As clearly appears from Figs. 1, 3, 4, 5 and 6, all of the horizontal convolutions extend the full length of the casting. The horizontal convolutions B and D cross all of the stops both main and limiting, thus dividing the stops into what may be considered three sections. Where the horizontal convolutions B and D cross the stops, the metal is extended inwardly to form V or U shaped sections 20, 21 and 22, the sections 20--20 in the end stops being deeper than the sections 22 in the limiting stop, but not as deep as the sections 21 in the main stop. It will be noted that the vertical portions of the horizontal convolutions B and D are in the back or outer plane of the casting and adapted to bear against the sill to which the casting is secured. Consequently, said portions of the convolutions B and D are provided with a series of rivet holes 23 disposed on opposite sides of all the stops and opposite the rivet holes 23, the horizontal convolutions B and D are preferably widened vertically as indicated at 24 and 25, to thereby better accommodate the riveting tools employed in attaching the castings. On account of the bends or sections 20, 21 and 22 in the horizontal convolutions B and D, substantially triangular sections 26, 27 and 28 are formed in the horizontal webs of the casting adjacent thereto, which thus provides an exceedingly strong casting to resist the blows imposed upon the stops, since the vertical walls or faces of the stops are braced by these triangular sections.

From examination of Figs. 1, 4 and 5, it will be apparent that the upper convolution A forms an upper guide for the followers between the stops since said convolution between the front ad rear main stops is extended outwardly beyond the guiding surfaces 29--29 for the followers.

By means of the arrangement of vertical and horizontal convolutions, above described, it will be noted that a casting of relatively great thickness is provided without producing any thick section of metal. Thus there are portions of the horizontal convolutions in the outer or back plane of the casting fitting against the sill, portions in a plane spaced from the back plane by which the guiding surfaces 29 are formed, and other portions in planes still farther removed from the back plane of the casting, as for instance in the outer faces of the main and limiting stops. The outer faces of the stops are not in the same plane because of the fact that it is desirable to make the center post 11 deeper than the end stops in order to form a fulcrum for the yoke of the draft rigging when the yoke and draw bar are swung radially. It will be noted that all of the vertical and horizontal convolutions are open either to the front or back and that there are no undercut surfaces whereby the casting may be made without the use or necessity of cores, thus minimizing the expense of casting. It will also be noted that the metal is of uniform section throughout, thus eliminating casting strains and annealing strains, thereby minimizing the number of defective castings due to imperfections in the casting and annealing operations. By the use of the horizontal convolutions, a great portion of the metal is placed in the form of horizontally extending webs, thus greatly strengthening the casting against buffing and pulling shocks and at the same time strengthening the casting against bowing or buckling laterally.

I claim:

1. A stop casting for draft riggings consisting of a web of metal having a series of horizontal convolutions therein, some of said horizontal convolutions having vertically spaced portions thereof forming riveting areas in the outer plane of the casting, said convolutions having inwardly extending, angled braces intermediate said spaced portions, each of said braces consisting of integral portions of said convolutions forming substantially a V in horizontal section.
2. A stop casting for draft riggings having a series of vertical convolutions therein forming stops, and a plurality of longitudinally extending convolutions, some of the horizontal convolutions extending rearwardly to the outer plane of the casting to thereby form vertically separated riveting areas, the portion of said horizontal convolutions between the riveting areas being

formed with inwardly extended angled braces of substantially V-shape in horizontal section, the latter being located within the stops.

3. A stop casting for draft riggings consisting of a web of substantially uniform thickness throughout and having embodied therein a series of vertical convolutions forming main and limiting stops and a series of horizontal convolutions, alternate horizontal convolutions including the top horizontal convolution being open to the back of the casting and the remaining horizontal convolutions being open to the front of the casting, said top horizontal convolution forming an upper guiding surface for followers operating between the main stops.

4. A stop casting for draft riggings consisting of a web provided with a series of vertical convolutions therein forming front, rear and middle main stops and limiting stops intermediate the main stops, the middle stop being deeper than the end stops, said casting having also included therein two horizontally extending convolutions open to the inner face of the casting, said horizontal convolutions extending from end to end of the casting and crossing the stops, the horizontal convolutions within the stops being provided with inwardly extended angled braces of substantially V-shape in horizontal section, said braces varying in depth according to variations in the depths of the stops.

5. As an article of manufacture, a stop casting for draft riggings, having a web of substantially uniform thickness throughout, said web being provided with a series of vertical bends extending alternately inwardly and outwardly to form main and limiting stops, the web of the casting being provided also with a pair of grooves extending longitudinally throughout the length of the casting and across said stops, the casting at the bottoms of said grooves being adapted to bear against a draft sill to which the casting is adapted to be secured, said grooves being located above and below the center of the casting to thereby leave the central portions of the outer faces of the stops suitable for bearing surfaces on a level with the center line of draft.

In witness that I claim the foregoing, I have hereunto subscribed my name this 18th day of Sept., 1916.

JOHN F. O'CONNOR.
